UNITED STATES PATENT OFFICE.

JASPER LEE DERN, OF PHILADELPHIA, PENNSYLVANIA.

CHOCOLATE-COATING MACHINE.

SPECIFICATION forming part of Letters Patent No. 691,610, dated January 21, 1902.

Application filed October 3, 1901. Serial No. 77,478. (No model.)

To all whom it may concern:

Be it known that I, JASPER LEE DERN, a citizen of the United States, residing in Philadelphia, Pennsylvania, have invented certain Improvements in Chocolate-Coating Machines, of which the following is a specification.

My invention relates to certain improvements in machines for covering articles with a coating or film of any desired substance, and more particularly to an improved machine for coating candies with chocolate.

The object of my invention is to provide a machine which shall coat candies with chocolate in a more efficient manner than has hitherto been possible, thereby securing a product of improved quality and that at a reduction in the cost of manufacture thereof. This object I attain as hereinafter set forth, reference being had to the accompanying drawings, in which—

Figure 1 is a plan view of my improved machine with the casing which normally incloses its upper portion removed. Fig. 2 is a front elevation of the machine. Fig. 3 is a sectional elevation of the machine, taken on the line 3 3, Fig. 1; and Fig. 4 is a sectional elevation on the line 4 4, Fig. 1.

In the above drawings, A is the body of the main casing of the machine, supported on two metallic frames or standards A', these latter serving to support the main driving-shaft B and a counter-shaft B'. As shown in Fig. 1, the main casing of the machine consists of a circular vessel, preferably of iron, on which is supported a kettle or melting-pot a, there being a space between the main casing and this kettle in which is a coil of pipe a', connected through an inlet-pipe a², extending through the bottom of the casing A to any suitable source of hot-water or steam supply. At the center of the bottom of the melting-kettle a is a shaft a³, having on its end a spider to which are bolted arms a⁴, these having their ends turned up at right angles to their length, so that they are in close proximity to the bottom and sides of the kettle.

There are upwardly-projecting fingers or pins a⁵ on each of the arms, as shown, and it will of course be understood that the number and arrangement of these may be altered in any of the constructions commonly known

to the art. There is a casting a⁶ fixed in an opening in the bottom of the main casing, through which the shaft a³ extends, and there is a stuffing-box a⁷ provided between the said shaft and the casing to prevent leakage of material from within the kettle a. The lower end of the shaft a³ carries a bevel gear-wheel b, meshing with another gear-wheel b', fixed to a sleeve b⁸, loosely supported upon the shaft B'. This sleeve carries a sprocket-wheel b⁴, placed in line with a second sprocket-wheel b⁵, preferably smaller in diameter and fixed to the main driving-shaft B. There is a pipe a⁸, provided with a valve opening into the space between the kettle a and the interior of the casing A, and this latter is also provided with an outlet a⁹, through which liquid may be drawn off from the space between the kettle and said casing.

It will be noted that the main casing A extends beyond the circular outlines of the melting-kettle a, taking a rectangular section and forming a vessel the shape of a section of a cylinder. The middle of the kettle a extends into this vessel, the whole having a flange around its upper edge and being retained in position within the casing A by means of a piece c, between which and the top edge of the casing said flange is confined. Attached in any suitable manner to this piece c and extending above and inclosing a space for the melting-kettle proper is a second casing C, the same being provided with three hinged doors c', c², and c³, respectively, through which material to be melted and trays containing the objects to be coated may be introduced into the chamber thus formed, of which the melting-kettle forms a part. Supported upon the edge of the main casing A and within the casing C, which is shown removed in all of the drawings except Fig. 4, are two pairs of standards or guides d, each pair having vertical surfaces between which a slide or cross-head d' is placed, there being a cross-piece d² joining the two cross-heads of the machine.

There are pins or bolts d³ upon each of the cross-heads, to which are attached connecting-rods d⁴, the other ends of these latter being engaged by crank-pins d⁵ on gear-wheels d⁶, revolvably supported on the sides of the casing A. These gear-wheels are operated

by pinions b^6 , fixed to the counter-shaft B' . Said shaft is in turn operated from a sprocket-wheel b^7 , connected by a sprocket-chain to another sprocket-wheel b^8 , loosely carried on 5 the main shaft B . By means of a treadle e any desired form of clutch, as E , may be made to engage the sleeve upon which the sprocket b^8 is carried, thereby causing it to revolve and actuate the counter-shaft B' and its attached mechanism.

Returning to the cross-piece d^2 , which connects the cross-heads d , it will be seen from Fig. 1 that there are lateral extensions near each of its ends, and each of said extensions 15 carries depending bars or rods f , supporting on their lower ends a plate F' . Also fixed to the lower ends of the rods f are lugs f' , through which and the plate F' pass rods or bars f^2 , these being provided with collars f^3 and carrying springs f^4 , confined between said collars and the lugs f' . There are rods d^7 extending between the upright standards d , and the vertical rods f^2 are of such length 20 that they come into engagement with the rod d^7 at one portion of their path of movement, the lower ends of the rods f^2 carrying a rectangular frame or carrier F . Held by screws to the upper edge of the plate F' farthest from the door c^2 are curved pieces f^5 , placed 25 as shown in dotted lines, Fig. 1. The curved portion of the said pieces extends toward a carrier H far enough to just clear the same as their supporting-plate F' is lowered in a manner and for a purpose to be described 30 hereinafter.

Upon each side of the casing C is a system 35 of rods and levers $g, g', g^2, g^3, g^4, g^5$, and g^6 , these being operated from the cross-heads d' by means of a rod g^7 , extending through the 40 casing C . The free ends of the rods g^2 and g^6 are pivoted to the doors c^2 and c^3 , respectively, of the casing C , the said doors being 45 opened or shut, according as the cross-heads are at the upper or lower portions of their stroke. A second pair of standards h is also supported from the casing A within the casing C , their upper portions being extended laterally and providing bearings for a pair of 50 vertical rods h' , the said standards also providing horizontal bearings for a shaft H' . The upper parts of the rods h' are connected by a cross-bar h^2 , and there is an open carrier H supported from their lower ends.

There are star-wheels h^3 fixed to the shaft 55 H' just under the cross-bars h^2 , which normally rest upon said wheels, and there is a pulley-wheel h^4 upon the outboard end of the said shaft, which is bolted to a smaller pulley-wheel on the shaft I' , carried in bearings 60 in the main standard or frame of the machine A' . This latter shaft has fixed to it star-wheels i , upon which rest cross-bars i' , connecting vertical rods i^2 , supported in suitable bearings in a casting i^3 , fixed to the main 65 frame A' . These rods have collars i^4 fixed to them, and there are springs i^5 confined between these collars and the upper portion of

the casting i^3 . The upper ends of the vertical bars i^2 are connected by a cross-bar i^6 , and to these bars castings i^7 are pivoted, there being 70 projections i^8 on the said castings, which engage with the said cross-bars. These castings support between them a frame or carrier I , similar to the carriers F and H , and are attached to said carrier at a point somewhat back 75 of the central line, so that the overhung weight of the outer edge of the carrier keeps the whole horizontal and the stop i^9 against the projection of the cross-bar i^6 . There are coils of 80 steam-pipes k supported from the upper part of the sides of the interior of the casing C . These are connected in any suitable manner to a source of supply.

In operation the space between the casing A and the kettle a is filled with water, and 85 steam is introduced into the coils of the pipe a' . Chocolate or other material with which it is desired to coat candies is placed within the kettle through the opening closed by the door c' and is melted therein. The main 90 shaft B is now set in motion, power being applied to the driving-pulley, and this revolves the arms a^4 through the mechanism above described, keeping the melted contents of the kettle a mixed and preventing any possible 95 burning. A tray containing articles to be coated is now introduced through the open door c^2 on the carrier F , and the treadle e is depressed by the foot of the operator. This causes motion to be imparted to the small sprocket-wheel 100 b^8 upon the main shaft B , and this in turn revolves the shaft B' , and with it the pinions b^6 . These are allowed to revolve long enough to cause the gear-wheels d^6 to accomplish one complete revolution, after which the clutch 105 E is automatically thrown out of engagement with the sleeve carrying the sprocket b^8 , and this part of the apparatus remains out of action until the treadle is again depressed. The movement of the gear-wheels d^6 has caused 110 the cross-heads d' to move down and then up in their guides d , thus also carrying down the cross-piece d^2 and dipping its carrier F , with the tray of candies, into the melted substance 115 within the kettle. It will be noted that as the cross-heads, with the cross-piece d^2 and its suspended parts, begin a downward stroke the plate F' lowers until it is stopped by contact with the upper surface of the tray containing the candy, which is placed on the 120 carrier F , and it will be noted that this tray is kept tightly pressed against the said plate F' by means of the upward action of the springs f^4 acting through the rods f^2 . After the carrier F and its tray have been dipped and as 125 it is approaching the top part of its stroke the rods f^2 contact with the cross-bars d^7 , causing the carrier F to be held stationary, while the plate F' continues its upward motion for a short distance. It will be noted that at the 130 beginning of the downward motion of the cross-heads d' the rod g^7 also moves downward, thus permitting the doors c^2 and c^3 to close, these being again opened when the said

cross-heads strike the same rod near the end of its upward motion. A second tray is now introduced through the door c^2 , this pushing the first tray originally on the carrier F onto the carrier H, and as the carrier F, with the second tray, is again made to descend into the kettle the curved pieces f^5 come in contact with the edge of the first tray overhanging the carrier H and push it onto the said carrier.

It will be seen from Fig. 1 that there is a pulley b^9 at one end of the driving-shaft B, and this is belted to the pulley i^9 on the shaft I', from which motion is transmitted through the pulley i^{10} to the pulley h^4 on the shaft H'. This revolves the star-wheels h^3 , and thus causes a continuous vibration of the cross-bar h^2 , together with the attached carrier H, on account of the successive blows struck upon the under surface of said cross-bar by the projections of the star-wheels. This action very effectually imparts rapid vibrations or a series of comparatively violent jars to the candy-containing tray on said table, and the surplus particles of comparatively dried chocolate or other substance adhering to the surface of the candies in said tray are effectually dislodged and fall back into the kettle. Should this vibration displace the first tray upon the carrier H toward the reciprocating mechanism of which the carrier F forms a part, said first tray is pushed back into place by the curved pieces f^5 as the carrier F and its plate F' rise from a dip in the kettle. In the meanwhile the carrier F has again been dipped into the kettle and a third tray introduced into the casing C through the door c^2 . This in turn has pushed the second tray from the carrier F onto the carrier H and has pushed the first tray from the carrier H within the casing C through the door c^3 onto the carrier I. A rapid jarring vibration is given to this latter carrier through the agency of the star-wheel i , upon which said carrier is supported, and whatever particles of material still remain upon the candies are finally dislodged and caught in the cylinder-like vessel under the carrier I. A piece of oiled paper is now placed over the first tray of candies and by pressure upon the outer edge of the carrier I it is made to revolve, and the said candies are deposited upon the oiled paper and removed.

It will be understood that while the machine is in operation steam or other heating fluid is circulated through the pipes k , keeping the interior of the chamber comprised by the casing C and the kettle a at any desired temperature, thus making it possible to remove the adhering surplus particles of chocolate or other material from the candies before the said chocolate has hardened too greatly to render this impossible.

It will thus be seen that the above-described machine is a decided improvement in the art, for where it has been customary to maintain the room in which machines of this charac-

ter were operating at a high temperature simply for the purpose of preventing too rapid hardening of the coating material I am enabled to close the machine and accomplish the same object at a greatly-lessened expense and in a much more advantageous manner. By the system of automatically-operated doors employed I am enabled to retain the heat within the casing and to operate the same in a most efficient manner.

I claim as my invention—

1. In a machine of the character described, the combination of a kettle, means for heating the same, a carrier for supporting a tray of objects to be coated, a casing inclosing said carrier thereby forming a chamber of which the kettle is a part, with means for causing the carrier to descend into the kettle at will, substantially as described.

2. In a machine of the character described, the combination of a kettle, means for heating the same, a carrier for supporting a tray of objects to be coated, a casing inclosing said carrier thereby forming a chamber of which the kettle is a part, means for heating the interior of the casing other than the means for heating the kettle, with means for reciprocating the said carrier in a vertical plane at will and thereby causing it to enter said kettle, substantially as described.

3. In a chocolate-coating machine, the combination of a kettle, means for heating the same, a carrier supported over the kettle for carrying a tray containing objects to be coated, a device for removing surplus material from said objects after they have been coated, a casing inclosing the carrier and the said device, the same forming a chamber of which the kettle is a part, and means for reciprocating the carrier so that it enters the kettle and means for operating the device for removing surplus material from the objects coated, substantially as described.

4. In a machine of the character described, the combination of a kettle, a closed casing over the same, a carrier over the kettle within the casing, with means for reciprocating it at will so that it enters the kettle, doors on the said casing for the admission of trays containing objects to be coated, and means for automatically opening said doors when the carrier is at the upper part of its path of movement, substantially as described.

5. In a machine of the character described, the combination of a kettle, a closed casing over the same, a carrier over the kettle within the casing, with means for reciprocating it at will so that it enters the kettle, doors on the said casing for the admission of trays containing objects to be coated, and means operated by the carrier-reciprocating mechanism for automatically opening said doors as the carrier approaches the upper portion of its path of movement, substantially as described.

6. In a machine of the character described, the combination of a frame, a kettle, a carrier over the same, means for reciprocating the

carrier and for causing it to enter said kettle, means for retaining objects in position on a tray placed on said carrier when the whole is lowered into the kettle, said carrier being constructed to contact with a fixed portion of the frame and to be stopped thereby before it reaches the top of its stroke, said reciprocating means with the retaining means being constructed to continue moving after the carrier has come to rest, substantially as described.

7. In a machine of the character described, the combination of a kettle, standards on opposite sides of the same, a frame constructed to be reciprocated in a vertical plane on said standards, a plate rigidly attached to the frame and a carrier resiliently held thereto, with means for causing the plate to move down upon a tray on said carrier and for moving the whole into the kettle, said plate being raised from the carrier after the latter has ceased moving, substantially as described.

8. In a machine of the character described, the combination of a kettle, a casing attached to and over the same forming a chamber of which the kettle is a part, a carrier constructed to hold a tray containing objects to be coated, means for moving said carrier into the kettle, a second carrier, means for vibrating said second carrier, both of the carriers being within the said casing, and doors in the casing opposite to the carriers, with means for automatically opening and closing said doors, substantially as described.

35 9. In a machine of the character described, the combination of a kettle, a casing attached to and over the same forming a chamber of which the kettle is a part, a carrier constructed to hold a tray containing objects to be coated, means for moving said carrier into the kettle, a second carrier, means for vibrating said second carrier, both of the carriers being within the said casing, a third carrier revolvably supported outside of the casing, means for vibrating the same, said third carrier being placed to receive a tray as it is delivered from the second carrier, substantially as described.

10. In a machine of the character described, 50 the combination of a kettle, a casing surrounding the same, heating means within the space between the kettle and said casing, a second

casing extending above the kettle forming a chamber of which the interior of the kettle is a part, heating means in the upper portion of the second casing, two carriers within the said chamber, means for reciprocating one of the same so that it may be made to enter the kettle at the will of the operator, and means for vibrating the second carrier, substantially as described.

11. In a machine of the character described, the combination of a kettle, a carrier for carrying trays of articles to be dipped, supported over said kettle, a second carrier at the same level as the first carrier, means for lowering said first carrier into the kettle and then returning it to its original position, and means on said carrier for moving a projecting tray fully upon the second carrier as the first carrier is lowered into the kettle, substantially as described.

12. In a machine of the character described, the combination of a kettle, a carrier for carrying trays of articles to be dipped, supported over said kettle, a second carrier at the same level as the first carrier, means for lowering said first carrier into the kettle and then returning it to its original position, a device constructed to engage a tray projecting over the edge of the second carrier and move it fully upon said carrier both as the first carrier is raised and lowered, substantially as described.

13. In a machine of the character described, the combination of a kettle, a carrier for supporting trays of articles to be dipped held over said kettle, a second carrier at the same level as the first carrier, means for lowering said first carrier into the kettle and then returning it to its original position, and pieces fixed to the first carrier projecting toward the second carrier constructed to engage a tray projecting over the edge of the second carrier and move it fully upon said carrier as the first carrier is raised or lowered, substantially as described.

In testimony whereof I have signed my name to this specification in the presence of two subscribing witnesses.
